WINDING MACHINE WITH MECHANICAL CHARGING OF BOBBINS

Wilhelm Reiners and Gustav Kahlisch, Munich-Gladbach, Germany, assignors to W. Schlafhorst & Company, Munich-Gladbach, Germany

Application September 14, 1932, Serial No. 633,196
In Germany October 10, 1931

12 Claims. (Cl. 242—35.5)

This invention relates to certain modifications of our copending prior application Serial No. 516,448, filed February 17, 1931. In the invention described in the said prior application, the full bobbins to be unwound are first automatically brought up to the unwinding station by a travelling conveying device and are then automatically shifted over to the unwinding station.

The invention described in the present application has for its objects the following modified forms of the invention of the said prior application:

1. The full bobbins are deposited from a conveyor upon individual stationary bobbin receivers in front of the unwinding stations, which receivers may be of trough or other shape, the bobbins being then shifted automatically or by mechanical means to the peg-shaped bobbin holders.

2. A plurality of full bobbins are shifted onto the bobbin holders simultaneously and positively by means of a common shifter.

3. A plurality of full bobbins brought to the several unwinding stations by a travelling conveyor in the form of a chain, a belt, or the like, are shifted by means of a separate lifting device in combination with a common shifter acting simultaneously for a plurality of unwinding stations.

4. The full bobbins are deposited by means of a travelling magazine upon stationary rests in front of the several bobbin stations, from which rests they may be individually shifted to the holders in succession by means of a travelling shifter or be shifted simultaneously by a common shifter.

5. The mechanical device by which the bobbins are shifted from their rests onto the pegs is made to advance the star-shaped peg holder one position on its return movement.

The drawings show various forms of embodiment of the invention.

Figs. 1 and 2 are respectively front and side elevations of a travelling bobbin magazine showing a holder for the bobbins.

Figs. 3, 4 and 5 are respectively a front elevation, a side elevation, and a plan view of a travelling conveyor in the form of an endless chain, showing bobbin holders associated therewith.

Fig. 6 shows a vertical section of one form of embodiment of a winding machine equipped with the devices shown in Figs. 3, 4 and 5.

Fig. 7 is a side elevation of the winding machine shown in Fig. 6.

Figs. 8 to 14 show a modified device with an endless conveyor chain and bobbin holders, Figs. 8, 10 and 12 to 14 being cross sections in various

positions of operation and Figs. 9 and 11 being side elevations in two positions.

Figs. 15, 16 and 17 are respectively a cross section, a side elevation, and a plan view of another form of machine having a conveyor in the form of a travelling bobbin magazine and stationary bobbin rests beside the bobbin holders.

Figs. 18 to 20 are respectively a cross section, a side elevation and a plan view of a conveying device in the form of an endless chain, showing bobbin holders and a special feeler mechanism for detecting bobbins not completely unwound.

Fig. 21 is a cross section of the same device modified for electrical operation.

Figs. 22 and 23 are respectively a cross section and a partial side elevation of the end of a conveyor mechanism showing devices for automatic control of the various machine movements.

Figs. 24 and 25 show in vertical section and side elevation respectively a machine having a stationary trough to receive the bobbins to be mounted on the holder, with a swinging shifting device for shifting the bobbins onto the holder and advancing the holder one position on the return movement.

Figs. 1 and 2 show the first embodiment of the invention. In these figures 1 is a magazine for the full bobbins, which travels along past the unwinding stations. 2 are the full bobbins which are urged toward a star-shaped single feed device 4 by an inclined bottom 3 of the magazine. The magazine 1 is moved past the unwinding stations by means of a screw spindle 5 driven by suitable means not shown and engaged by an internally threaded bush 6 on the magazine. In place of the screw spindle 5 there can, of course, be used a chain, a belt, a rope, or any other suitable means for imparting motion to the magazine. The magazine 1 can be guided by means of rollers riding upon tracks 7 and 8. The periodic advancement of the star-shaped single feed device 4 is accomplished by lugs 10 on a stationary rail 9, the single feed device being advanced one position for each unwinding station. On the magazine 1 is a second inclined plane or drop chute 11, upon which the bobbins 2 released from time to time by the feed device 4 can slide down, impelled by their own weight, to be pegged upon the ready standing empty peg of the holder 12. Since the bobbin 2 is now mounted upon its holder 12 it must be released from the holder 13 on the slide 11 as the magazine 1 continues to travel, and for this purpose the holder 13 is constructed as a spring flap. The bobbin holders 12 are made in the form of star-

80

85

90

95

100

105

110

shaped supports, as in the aforesaid copending application, which in this case also are free to rotate about an axis 14 and are held in their various positions by a retaining device. As in the prior application there is a deflector 15 on the travelling magazine 1, which takes care of the advancement of the star-shaped bobbin holder 12 to its next working position, the empty bobbin being removed from its holder at the same time by a stripper 16.

The form of machine described above provides for the transfer of the unwinding bobbins to their holders simply by the weight of the bobbins themselves, without the use of any positively 15 acting shifter.

Figs. 3, 4 and 5 show a second form of the machine. Here, in contrast to the first embodiment, the transfer of the bobbins takes place, not by their own weight, but by means of a 20 shifter. This is similar to the aforesaid prior application, with the exception that in the present case the bobbins are not individually transferred, but a plurality of them together are positively pushed onto their holders by a common 25 shifter. The operation is as follows:

The bobbins 2 are automatically extracted from a stationary magazine 57 (Figs. 6 and 7), preferably arranged at one end of the machine, by an endless conveyor chain 17 driven by shaft 30 300 and are automatically carried to the several unwinding stations. The bobbins are carried upon the conveyor chain on seats 60. As soon as bobbins have arrived at all the unwinding stations to be served, the conveyor chain 17 35 automatically stops. Now the bobbins 2 are shoved by a stroke of the shifter 18 onto their holders 12a rotatably mounted upon shaft 14, the shifter serving a plurality of unwinding stations. Shifter 18 is mounted upon rods 19 slidably supported in bearings 20. The ends of rods 19 are toothed and mesh with segments 21 fixed upon a rock-shaft 22. The rock-shaft 22 may be operated by a hand lever, as indicated by dotted lines at 23 in Fig. 3. Between conveyor 17 40 and the holders 12a runs a channel bar 52 forming part of the frame of the machine. This channel bar supports guide plates 47 opposite each holder, which guide the bobbins onto the holders. Upon conveyor chain 17 is mounted a deflector 15a which engages the downwardly directed pegs of holders 12a as the conveyor travels along and advances each holder one peg division, moving the full bobbins into their upright unwinding positions. For better support the deflector 15a is guided by pulleys 53 and 54 running upon channel bar 52. In place of the manual control shown in Fig. 3, shifter 18 may be controlled entirely mechanically and uninfluenced by the will of the person operating the 45 machine by means of the device shown in Figs. 22 and 23. In this case there is fixed upon the drive shaft 24 of the machine (Fig. 22) a worm 25, which drives a worm wheel 26 on shaft 27. On the shaft 27, which is rotatably mounted in 50 the frame of the machine, there is fixed another toothed wheel 28. The latter is in mesh with a clutch wheel 29 of shaft 300, the wheel 29 having its hub constructed as one clutch half. On the same shaft 300 is mounted a displaceable 55 complementary clutch half 31, which is operated by a two-armed lever 32 pivotally mounted at 33 on the frame of the machine and engaging at its lower end the slidable half 34 of a second clutch. The shaft 300 is rotatably mounted in 60 the frame of the machine at 55 and 56. The

clutch half 34 operated by the lower arm of lever 32 engages in its complementary clutch half in the position shown in Fig. 22, the latter clutch half being formed on the hub of a toothed wheel 35. Toothed wheel 35 is rotatably mounted on shaft 36, while the two clutch halves 31 and 34 can only slide upon their respective shafts 300 and 36 and cannot rotate thereon. On the shaft 36, which is journalled in the machine frame at 37 and 38, is a drum 39 which has on its periphery a spiral cam slot 40. In the slot engages a roller 41 mounted on a pin on lever 44, which is fastened upon shaft 22. The cam drum 39 derives its motion from shaft 27 through toothed wheels 28, 29, 42 and 35. Upon shaft 300 there is also a sprocket wheel 43 which drives the endless conveyor chain 17. According to whether the clutch half 31 or 34 is engaged with its toothed wheel 29 or 35, either the conveyor 17 or the shifter 18 will be operated. Both motions follow each other positively, therefore they can never take place simultaneously, whereby an absolutely certain operation of the transfer mechanism is assured. The automatic throwing in and out of the two operations is accomplished 100 in the following manner:

On the upper end of clutch lever 32 is mounted a cam nose 45. On the deflector 15b, which serves for a plurality of bobbin holders 12a, is a complementary nose 46. As soon as the deflector has 105 operated the last bobbin holder 12a of the number of bobbin stations served by it, the nose 46 strikes the nose 45 of the clutch lever 32 and thereby brings this lever and the clutch half 31 into the thrown out position shown in Fig. 22. 110 Hereby the conveyor chain 17, which has been running up to this time, is brought to a standstill. However, at the same instant the clutch half 34 at the lower end of the same lever 32 is thrown into its engaged position shown in Fig. 115 22 and thereby the cam drum 39 moves the shifter 18 toward the machine. The bobbins 2 standing ready upon the seats 60 of conveyor 17 are shoved in the direction of the bobbin holders 12a and are finally automatically pegged upon 120 them. On the way from the conveyor chain 17 to the bobbin holders 12a the bobbins can be supported from below by stationary intermediate guide plates 47, whereby an accurate guiding of the bobbins 2 is assured, even though the conveyor chain 17 may wear and thereby require the insertion of enlarged parts. By further travel of the cam drum 39, the shifter 18 is again brought 125 into its starting position shown in Fig. 22. As soon as this is accomplished the lever 32, the lower end of which carries a nose 48 engaging in a concentric slot 49 in the face of the cam drum 39, is thrown out by the striking of nose 48 against a switching projection 50 in the slot 49 (Fig. 23). During this movement the lower end 130 of lever 32, which is provided with a wedge-shaped nose, slides over a spring bolt 51 slidably mounted on an arm of bearing 37. The motion of lever 32 caused by this operation serves to throw in again the upper clutch half 31 and thereby starts the conveyor chain 17 for the further automatic conveyance of another complement of full bobbins to their bobbin stations. In order to insure an accurate guiding and operation of the deflector 15 which, in this embodiment, is mounted on the conveyor chain 17, the deflector is guided by rollers 53 and 54 travelling upon stationary channel bar 52 as described with reference to Figs. 3 and 5. By the above 135 described positive drive and the automatic con- 140

150

trol of the shift motions the operation of the machine is rendered independent of the person serving it; the periodic sequence of the operative procedures can be determined in advance, whereby the attainment of the highest possible output of the machine and worker is achieved.

In Figs. 6 and 7 the second described embodiment of the invention is shown on a cross winding machine. The drive for the automatic operation of conveyor chain 17 and shifter 18 is omitted from both figures, since it can be fully understood from Figs. 22 and 23.

As can be seen from Fig. 7 there are mounted on the conveyor chain 17 two deflectors 15a for advancing the bobbin holders 12a, for the chain in this case is designed for two shifts.

In Fig. 7 is further shown the manner in which the full bobbins 2 are extracted from the stationary magazines 57. For this purpose the conveyor chains 17 can be provided at each unwinding station with projections or lugs 58. Each lug releases a lever 59 on the stationary magazine 57, which thereby releases a bobbin 2 from its locked position in the stationary magazine and lets it fall upon the corresponding support 60 of the conveyor chain 17.

In short machines these collector magazines 57 may, in certain cases, be dispensed with, the bobbins then being laid upon the conveyors by hand at the head of the machine or at any other suitable place.

Figs. 8 to 14 show the third embodiment of the invention. Here the full bobbins 2 are likewise taken by the endless chain 17a from a stationary magazine (such as 57 of Fig. 7) at the end of the machine and conveyed to the several unwinding stations, the bobbins being carried in rests 60a. In contrast to the second embodiment described the conveyor chain 17a is here mounted low. Now in order to bring the full bobbins 2 to the position shown in Fig. 10 for the purpose of shifting them to the holder 12a, the shifter 18a and another rail 61, operate together as a lifting device for the bobbin 2. For this purpose bobbin rests 62 are provided on the shifter 18a, while recesses 63 in the rail 61 serve as seats. For lifting the shifter 18a and the rail 61 into the transfer position shown in Figs. 10, 11 and 12, there are fastened upon the operating rods 19a of shifter 18 special segment levers 64, for the operation of which the operating rods 19a are rotatably mounted at 20a. The segments 64 are linked together by means of a link 65 connected at 66. Now if a pull is exerted in the direction of arrow a, either by hand or mechanically, the segments 64 are turned to the position shown in Figs. 10, 11 and 12. Since the shifter 18a and the rail 61 are connected together by a common frame 67, the shifter and rail are raised together, whereby they raise all the full bobbins from the bearings 60a on chain 17a and bring them to the transfer position (Fig. 12), in the same way as has already been described in connection with the second embodiment of the invention. Fig. 13 shows the bobbin raising and shifting device lowered again from the transfer level, and Fig. 14 shows them moved forward again into the starting position shown in Fig. 8. In this case also, all the motions of the bobbin conveying mechanism can follow in sequence mechanically and automatically, in the manner described in connection with Figs. 22 and 23.

In Figs. 15 to 17 is shown another embodiment of the invention. Here the conveying device for the full bobbins is in the form of a travelling magazine 1e, as in the first embodiment, but here

the full bobbins 2 fall directly upon stationary rests 84 in front of the unwinding stations, each rest holding its bobbin coaxial with the extended axis of the peg of the bobbin holder 12a which is to receive the bobbin. After the travelling magazine 1e has reached the end of its track and has deposited all of the full bobbins and has returned to starting position, the bobbins can be shoved onto the pegs of the bobbin holders either individually in sequence by a travelling shifter, as in the aforesaid prior application, or, as shown in Figs. 15 and 16, a plurality of bobbins can be positively pushed onto the bobbin holders by a shifter 18e. As shown in these figures the rest 84 is fastened upon the shifter 18e and moves therewith. The shifter can be operated in the manner which has already been described before by means of an actuating device 19e, 21e controlled by shaft 22. The operation and construction of the magazine 1e can be substantially the same as in the first embodiment of the invention. The newly pegged bobbins remain in horizontal position while the previous batch of bobbins is being unwound, when the magazine begins another trip and a deflector 15e mounted upon the front of the magazine advances the holders to bring the pegged bobbins to unwinding position and to bring new pegs to receiving position.

From the embodiments described above it will be seen that the shifter 18 for charging a plurality of unwinding stations simultaneously, or the various forms of devices for chuting the bobbins down under their own weight, receive the full bobbins either directly from the travelling conveyor, or indirectly from stationary rests, to which the bobbins are conveyed by a travelling bobbin magazine.

Figs. 18 to 21 show one form of an auxiliary device which has the purpose of preventing a charging and discharging of bobbin holders in which there are remnants of yarn not yet unwound, as occurs when the yarn breaks; the object being to permit this remnant to be completely unwound along with the others when the yarns of the next set of bobbins have been knotted to those on the winding packages. This inventive thought is utilized in the illustrative embodiment shown in Figs. 18 to 21 in the following manner.

90 is a feeler which can swing about a pin 91, 125 when, as it travels along the unwinding stations its nose 92 strikes against a remnant of yarn not unwound on account of breakage. The feeler 90 is mounted on a rigid holder 93, which in turn is secured to a special endless conveyor chain 75g, 130 the feeler being carried along by this conveyor chain past the unwinding stations. On the rigid holder 93 is also pivoted the deflector 15g for the bobbin holders 12a, similar to the one repeatedly referred to herebefore. The feeler 90 is in the 135 form of a bell crank lever, the short arm 94 of which is articulated to a pull rod 95. The latter engages at its other end the deflector 15g. Now if the travelling feeler 90, as it moves past the unwinding stations, is thrown out of the position shown in dotted lines in Fig. 20 into the position shown in full lines, on account of striking a remnant of yarn, the deflector 15g is simultaneously brought into the position shown in full lines in Fig. 20 through the action of the short arm 94 140 and the pull rod 95. In this latter position it cannot engage behind the lower empty peg of holder 12a, therefore an advancement of the holder is prevented, the remnant of yarn remaining in operative position on the holder to 150

be unwound and connected later to the new yarn. On the deflector 15g, in this form of the machine, there is a special hook-shaped downward extension 96, which serves the purpose of swinging out 5 a lever 97 in case the deflector 15g is swung out on account of the feeler 90 striking a remnant of yarn. There is a lever 97 for every unwinding station. These levers are mounted upon a common shaft 98. Upon the same shaft is fastened 10 a lever 99 below the stationary magazine 57g, to the free end of which lever is linked a thrust rod 100, the other end of which is articulated to a bell crank lever 101. The latter lever is pivotally mounted on the stationary magazine 57g and its other arm serves to throw in and out a clutch 102. The clutch 102 is mounted directly on shaft 103 of the star-shaped feeder 104 for the bobbins. The distributor is yieldably held in its several 15 positions of rest by a locking wheel 105 cooperating with a spring locking nose 106. If the feeler 90 swings out, under the influence of a remnant of yarn, then in the manner described above the clutch of the bobbin feeder is disengaged and no new bobbin is left for that station. Only when 20 the feeler 90 has left the yarn remnant of that unwinding station as the conveyor moves on is the clutch 102 again automatically thrown in and the further charging of the device with the new bobbins continued. The conveyor chain 17a and 25 shifter 18a, and rail 61 may be of the same type as shown in Figs. 10 to 14. In Fig. 21 is shown how, instead of the mechanical interruption of the delivery of bobbins in case the feeler 90 strikes a remnant of yarn, an electro-magnetic 30 interruption can be provided. This may be done, for example, by replacing the oscillating shaft 35 98 with a stationary contact bar 107, arranged so that in case of a depression of the lever 97a when the feeler 90 strikes a remnant of yarn 40 the opposite end of lever 97a strikes upon a second conductor 108, closing the circuit and causing the actuation of bell crank lever 101 by electro-magnet 109, so that for the corresponding 45 bobbin rest of the conveyor the delivery of a new bobbin is interrupted.

The shifter may also take the form shown in Figs. 24 and 25. It consists of a swinging bell crank lever 222, 223 at each unwinding station, which may be mounted under the trough or rest 50 224 upon which the bobbin 2 is deposited by the magazine 225. The bell crank levers of a group of unwinding stations, or of all unwinding stations on one side of the machine, may be mounted upon a common shaft 226. The free 55 end of the arm 222 of the bell crank lever lies directly in front of the bobbin 2 on rest 224 which is to be shifted onto the bobbin holder. The motion of the bell crank lever for shifting the bobbin onto the peg 24a of the holder which 60 stands in front of it may be imparted by a deflector on the conveyor of the kind shown in the aforesaid copending application. The charging motion of the bell crank lever may, however, be imparted by means of a pedal device consisting, for example, of a rod 227 slidably mounted 65 for vertical reciprocation in bearings 228, provided with a pedal 229, and normally held in operative position by a counter-weight or a spring 230. The rod 107 has a pin 231 which engages 70 in an elongated hole in arm 223 of the bell crank lever, the said arm carrying at its end a laterally yieldable spring switching pawl 232. Upon the return motion of the pedal device initiated by spring 230, the bell crank lever is moved back 75 simultaneously, the switching pawl engaging un-

der the downwardly directed peg and turning the holder so that the mounted bobbin 2 moves to the unwinding position and the empty tube 2a is stripped off by the stripper 30.

Having described our invention, we claim:—

80

1. In a device of the class described, a plurality of supply holders, means for distributing a plurality of bobbins respectively opposite said holders, and means to engage said distributed bobbins to shift them onto said holders.

85

2. In a device of the class described, a plurality of supply holders, means for distributing a plurality of bobbins respectively opposite said holders, and a common shifting device adapted to engage said bobbins and move them simultaneously onto said holders.

90

3. In a device of the class described, a plurality of supply holders, a plurality of bobbin rests respectively positioned opposite said holders and each adapted to receive a full bobbin, and a common shifting device for the bobbins on said rests, said shifting device having an upward motion to raise the bobbins from said rests and a transverse motion to push the bobbins onto said holders.

95

4. In a device of the class described, a plurality of supply holders, a plurality of bobbin rests each having a substantially fixed location opposite one of said holders, means for automatically depositing a full bobbin in each of said rests, and means for shifting the bobbins from said rests onto said 100 holders.

100

5. A device as described in claim 1, in combination with a feeler mechanism for detecting incompletely unwound bobbins, said feeler mechanism being adapted to prevent the charging with a new 110 bobbin of bobbin holders bearing incompletely unwound bobbins.

110

6. A device as described in claim 1, in combination with a single traveling feeler mechanism for detecting incompletely unwound bobbins, said 115 feeler mechanism being adapted to prevent the charging with a new bobbin of bobbin holders bearing incompletely unwound bobbins.

115

7. In a device of the class described, a plurality of supply holders, a plurality of rests for supporting full bobbins in preparatory positions opposite said holders, means for depositing individual full bobbins in said rests, feeler mechanism for detecting incompletely unwound bobbins on said holders, said mechanism being adapted to prevent the deposit of a bobbin on any of said 120 rests opposite a bobbin holder having an incompletely unwound bobbin, and means for shifting bobbins from said rests onto said holders.

120

8. In a device of the class described, a plurality of supply holders, means for distributing full bobbins to preparatory positions opposite said 130 holders, means for shifting said bobbins from said preparatory positions onto said holders, driving mechanism for said distributing and shifting 135 means, and a switching device for causing alternate operation of said distributing and shifting means by said driving mechanism.

130

9. In a device of the class described, a plurality of supply holders, said holders being movable 140 from a bobbin receiving position to a bobbin unwinding position, means for distributing full bobbins to preparatory positions opposite said 145 holders, means for shifting said bobbins from said preparatory positions onto said holders, driving mechanism for said distributing and shifting means, and a switching device for causing alternate operation of said distributing and shifting means by said driving mechanism, said switching device being further adapted to move 150

- said holders from receiving to unwinding position. 10. In a device of the class described, a plurality of supply holders, for supporting bobbins to be unwound, said holders being movable from unwinding position to bobbin receiving position and from bobbin receiving position to unwinding position, means for distributing full bobbins to preparatory positions opposite said holders, means for shifting said bobbins from said preparatory positions onto said holders, separate travelling switching mechanism for moving said holders from receiving to unwinding position and vice versa, and means for stripping bobbin tubes from said holders as they move out of unwinding position. 15. In a device of the class described, a supply holder, said holder being movable between a bobbin receiving position and a bobbin unwinding position, means for feeding new bobbins into a
